Primary Examiner — Jennifer Rivard*Assistant Examiner* — Alison M Ofstun(74) *Attorney, Agent, or Firm* — Gurr Brande & Spendlove, PLLC; Robert A. Gurr(57) **CLAIM**

The ornamental design for a hair styling tool, as shown and described.

DESCRIPTION

FIG. 1 is a front, top perspective view of the hair styling tool; FIG. 2 is a front elevation view of the hair styling tool; FIG. 3 is a rear elevation view of the hair styling tool; FIG. 4 is a right, side elevation view of the hair styling tool; FIG. 5 is a left, side elevation view of the hair styling tool; and,

FIG. 6 is a top plan view of the hair styling tool, the bottom plan being a mirror image thereof.

The broken lines shown in the drawings are for the purpose of illustrating portions of the article that form no part of the claimed design.

1 Claim, 4 Drawing Sheets(56)
